DESIGN FOR A DISPLAY COUNTER

Rush H. Kress, New York, N. Y., assignor to S. H. Kress and Company, New York, N. Y., a corporation of New York

Application April 3, 1944, Serial No. 113,123

Term of patent 14 years

(Cl. D80—2)

To all whom it may concern:

Be it known that I, Rush H. Kress, a citizen of the United States and residing at New York, in the county of New York and State of New York, have invented a new, original, and ornamental Design for a Display Counter, of which the following is a specification, reference being had to the accompanying drawing, forming part thereof, and in which:

The figure is a perspective view of the display counter, showing my design.

The rear of the cabinet, not shown in the drawing, is open.

I claim:

The ornamental design for a display counter, substantially as shown and described.

RUSH H. KRESS.
